UNITED STATES PATENT OFFICE.

ANDREAS J. PALMBERG, OF BOSTON, MASSACHUSETTS.

SCHOOL DESK AND SEAT.

SPECIFICATION forming part of Letters Patent No. 520,702, dated May 29, 1894.

Application filed September 11, 1893. Serial No. 485,236. (No model.)

To all whom it may concern:

Be it known that I, ANDREAS J. PALMBERG, a citizen of the United States, and a resident of Boston, in the county of Suffolk and State 5 of Massachusetts, have invented new and useful Improvements in Adjustable School Desks and Seats, of which the following, taken in connection with the accompanying drawings, is a specification.

10 This invention relates to improvements in adjustable school desks and seats and it is carried out as follows, reference being had to the accompanying drawings, wherein—

15 Figure 1, represents a side elevation of the invention. Fig. 2, represents a vertical section on the line 2—2 shown in Fig. 1. Fig. 3, represents a longitudinal section on the line 3—3 shown in Fig. 2. Fig. 4, represents a vertical section on the line 4—4, shown in 20 Fig. 1. Fig. 5, represents a horizontal section on the line 5—5, shown in Fig. 3; and Fig. 6, represents a detail side view of the key for unlocking the bolts by which the desk or its seat is held in position.

25 Similar letters refer to similar parts wherever they occur on the different parts of the drawings.

In the drawings A represents the desk base having standards B. B in which the uprights 30 C. C of the desk are vertically adjustable. In practice I prefer to secure to the uprights C. C a cross beam or lateral support C' to the rear portion of which is hinged at d the desk top D as shown.

35 E is an ink stand of any desired size or shape which is retained in a recess C'' in the cross beam C' and having its upper portion or neck projecting upwardly through a perforation D' in the hinged desk top D as shown 40 in Fig. 1, by which arrangement the said desk top may be swung upward to allow the scholar to take his seat or leave it without danger of spilling the ink contained in the ink stand.

The uprights C. C of the vertically adjustable desk are connected together by means of a vertical back C³ which is adapted to be automatically forced upward when released by the influence of a suitable spring C⁵, one end of which is attached to the base A and the 45 other end to the vertically adjustable back C³ as fully shown in Figs. 2 and 3.

F. F are spring pressed and laterally expansive locking bolts arranged in suitable guides on the adjustable back or desk support C³ and having their outer ends passing through 55 perforations in the uprights C. C and adapted to lock into notches or recesses b, b, b, on the interior of the standards B, B as shown in Fig. 2.

The bolts F. F are automatically held in 60 their outward locked positions by the influence of a suitable spring G as shown in Figs. 2 and 3. The inner ends of the locking bolts F, F are provided with lips or projections f, f adapted to be actuated by the key H shown 65 in Fig. 6, said key having a central pivot h, adapted to be inserted in a hole or recess C⁴ in the desk support C³. The key H is provided with side projections H', H', by means of which the lips f f are actuated for releasing the bolts F. F whenever it is desired to vertically adjust the position of the desk. All that is necessary to do for this purpose is to insert the pivot h, of the key into the notch or recess C⁴ when the key projections H', H', 70 75 will be located outside of the bolt lips f, f and by turning said key to the right the said bolts will be withdrawn from their locking recesses b, b in the standards B, B thus permitting the desk and its connections to be vertically adjustable 80 to suit the height of the scholar for which it is to be used.

I represents the base of the adjustable seat, and said base is longitudinally adjustable in guides in the desk base A to and from the desk 85 so as to enable the said seat to be easily adjusted to and from the desk according to the size or stoutness of the scholar that is to use the adjustable desk and seat. After the seat frame has been adjusted relative to the desk 90 it is only necessary to secure it in position preferably by means of set screws i, i, going through slotted perforations i', i', in the adjustable seat base I as shown in Figs. 2, 3, 4, and 5.

95 K is a floor secured in a suitable manner to the adjustable base portion I and adapted to serve as a support for the feet of the scholar. Said floor is preferably made removable so as to permit free access to the adjusting screws 100 i i in adjusting the position of the seat in a horizontal direction to and from the desk.

- L. L are standards secured to the adjustable frame I in which the uprights M M of the seat N are vertically adjustable, said uprights being connected by a back wall M'. 5 The said seat is automatically raised when released by the influence of a spring O, secured by one end to the back M' and by the other end to the lower base portion of the standards L. L in a manner similar to that 10 described for raising the desk.

For locking the seat in position after it has been vertically adjusted, I use a mechanism similar to that used for locking the desk in position after being similarly adjusted and I 15 have for this purpose shown a pair of spring pressed locking bolts P, P, passing through perforations in the seat uprights M, M and adapted to enter notches or recesses l, l in the guides or standards L, L as shown in Fig. 4. 20 The bolts P, P are automatically held in their expanded locked position by the influence of a suitable spring Q, as shown in Fig. 4.

The inner ends of the locking bolts P, P are provided with lateral lips or projections 25 p, p, and between the same is made a perforation m similar to the perforation C⁴ in the back of the desk support C³ for receiving the center h, of the key H, which serves for the purpose of unlocking the bolts P, P in the 30 same manner as described relative to the unlocking of the bolts F, F on the desk support. It will thus be seen that the desk is vertically adjustable as is also the seat and the

latter is horizontally adjustable relatively to the desk. 35

The desk top is hinged as described and adapted to inclose and protect the ink stand so as to prevent the latter from being accidentally overturned, the whole being constructed and arranged substantially as and 40 for the purpose hereinabove described.

Having thus fully described the nature, construction, and operation of my invention, I wish to secure by Letters Patent and claim—

In a school desk or seat, the combination 45 of standards notched on their inner sides, a vertically adjustable desk or seat provided with uprights guided in said standards and having oppositely arranged sliding bolts provided upon their adjacent ends with hook-shaped projections extending in opposite directions and adapted to be engaged by a forked key to retract said bolts, a spring arranged between the bolts and operating to force said bolts outward into engagement 50 with said notched standards, and a spring for raising said desk or seat, substantially as described.

In testimony whereof I have signed my name to this specification, in the presence of 60 two subscribing witnesses, on this 31st day of August, A. D. 1893.

ANDREAS J. PALMBERG.
